CLAIM

The ornamental design for a vehicle body, as shown and described.

DESCRIPTION

FIG. 1 is a perspective view of another embodiment of a vehicle body showing the new design;

FIG. 2 is another perspective view thereof;

FIG. 3 is a top plan view thereof;

FIG. 4 is a left side elevation view thereof;

FIG. 5 is a right side elevation view thereof;

FIG. 6 is a front elevation view thereof; and

FIG. 7 is a rear elevation view thereof.

FIG. 8 is a perspective view of yet another embodiment of a vehicle body showing the new design;

FIG. 9 is another perspective view thereof;

FIG. 10 is a top plan view thereof;

FIG. 11 is a left side elevation view thereof;

FIG. 12 is a right side elevation view thereof;

FIG. 13 is a front elevation view thereof; and,

FIG. 14 is a rear elevation view thereof.

The evenly spaced dash-dash broken lines illustrate features of the vehicle body that form no part of the claimed design.

The dot-dash pattern broken lines define boundaries of the claimed design and illustrate features of the vehicle body that form no part of the claimed design.

1 Claim, 12 Drawing Sheets
